UNITED STATES PATENT OFFICE.

WILLIS GRANT MURRAY, OF SAN FRANCISCO, CALIFORNIA.

VACUUM SYRUPING-MACHINE.

1,080,469.

Specification of Letters Patent.

Patented Dec. 2, 1913.

Application filed August 26, 1912. Serial No. 717,151.

To all whom it may concern:

Be it known that I, WILLIS GRANT MURRAY, a citizen of the United States, residing in the city and county of San Francisco, State of California, have invented certain new and useful Improvements in Vacuum Syruping-Machines, of which the following is a specification.

My invention relates to vacuum syruping machines, and its object is to provide a rapid and efficient means for syruping cans by the vacuum process, and to automatically receive, syrup and discharge the same in a safe and satisfactory manner.

For a clear comprehension of the invention reference should be made to the drawings accompanying this specification in which:—

Figure 1, is a plan view of the machine showing the syruping mechanism, adjusting screws, opening and closing trips for the valves and the pipe connection to the liquid reservoir, the open section disclosing a vacuum connection, the carrier head, and the receiving and discharging gears with broken sections of the table along which the cans are delivered to the machine and discharged therefrom. Fig. 2, is a front elevation of the machine showing the carrier head with the cans in place, the double reservoir with pipe connections, two-way valves with star control, opening and closing trips with cut-out for an empty section, the arrangement of the gears and sprockets for the receiving and delivering mechanism, the adjusting screws, a means for applying the power to operate the machine and the clutch control. Fig. 3, is a sectional view in elevation showing the double reservoir, the syruping pipe above and the vacuum pipe connection through the hollow shaft from below; the two-way valves with star control and the pipe connection to the double reservoir, the gear connected double adjusting screws for the elevation or depression of the syruping head, the ball bearing between the revolving mechanism and the base, the automatic lifting plungers and the means for applying the power to operate and control the machine. Fig. 4, is an enlarged detail view of the opening and closing trip with cut-out or empty section in its relative position to the star controlled two-way valve. Fig. 5, is a front end view in elevation of the star controlled two-way valve. Fig. 6,

is a sectional view of the two-way valve open to the vacuum pipe line. Fig. 7, is a sectional view of the two-way valve open to the syrup pipe line. Fig. 8, is a view of the two-way valve in cross-section after the star head has passed the closing trip. Fig. 9, is a sectional view of the star controlled two-way valve after it has passed the placing trip and is now in position to be opened to the vacuum pipe line.

The numeral 1, is used to designate a stand or base on which the mechanism is assembled.

2, is the syruping head with the double reservoir whose upper chamber 3, is the receiving tank, and the lower 4, is a means through which the suction is applied to produce the vacuum in the can prior to syruping the same. Radiating from the chamber 3, are the distributing pipes 5, 5, while from the chamber 4, the suction pipes lead, both ending in suitable connections to the star controlled two-way valves 7, 7. The numerals 8, 8, indicate the star heads controlling said valves.

9, is the carrier head with the flange 10, rigidly secured thereto, said flange having the depressions 11, 11, of suitable depth and shape to receive the cans and hold the same in position for syruping and delivery.

12, 12, are the plungers of the carrier head designed to bring the can into air-tight contact with the openings 13, 13, of the two-way valves 7, 7. To insure an air-tight connection with said openings the elastic cap 14, is provided.

15, 15, are the bearings or pockets in which the plungers 12, 12, are slidably mounted; rotatably secured in the lower end of said plungers are the small wheels or rollers 16, 16, so disposed as to engage and roll upon the track or rail 17. This track or rail is of differential height thereby causing the plungers to rise or fall at the proper time to receive the can, form the air-tight joint with the two-way valve, release and allow the same to be discharged as the carrier head with its assembled mechanism revolves.

18, 18, are the gear connected adjusting screws for raising or lowering the syruping head to suit the height of the can used.

19, is the driving sleeve to which the carrier head 9, is secured; while 19' is the ball bearing between the revolving mechanism

and the base. The driving sleeve 19, passes through the central bearing 20, and secured to the lower end thereof is the main driving gear 21. The power is applied to said gear 5 by means of the pinion 22, rigidly secured to the shaft 23, on the outer end of which the belt wheel 24, with the controlling clutch 24' is mounted. In the lower part of the base the webbed section 25, is secured, 10 in the center of which is the pocket 26. Entering this pocket through the stuffing box 27, is the upright hollow shaft 28; said shaft passing through the bearing thus formed enters the chamber 29, to which is 15 suitably attached the vacuum pipe line 30. On the outer end of the webbed member 25, the bearing 31, is secured, the said bearing having movably mounted therein the shaft 23, with its pinion 22, and the belt wheel 24, 20 with the clutch control 24'. In the bottom of the pocket 26, is a clean-out valve 32, for convenience in removing any accumulation of oil or sediment from the chamber 29. The upright hollow shaft 28, extends from 25 the chamber 29, through the driving sleeve 19, and ends with a taper fit in the syruping head 2; the said shaft is secured therein by the flanged cap screw 33, which forms an air-tight joint closing the upper end of the 30 upright hollow shaft 28.

Arranged on either side of the flanged cap screw 33, are the twin pipe connections 34, 34, entering the upper chamber 3, of the double reservoir. The center upright member of the twin connections indicated by the numeral 35, is joined to the supply pipe 37, by the rotatable union 36.

Rotatably mounted on the upright hollow shaft 28, between the carrier head 9, and 40 the syruping head 2, is the gear 38, connecting the adjusting screws 18, 18, by means of the pinions 39, 39. Mounted on one of the adjusting screws and rigidly secured thereto is the hand wheel 40, which provides a means for operating the same.

Rigidly secured to the driving sleeve 19, and below the bearing 20, is the gear 41, driving the pinion 42, and the shaft 43. On the shaft 43, the sprocket 44, is secured; 50 said sprocket being the means, (through a triangular chain connection,) for driving the loading gear 45, and the discharging gear 46.

Attached to the shaft of the loading gear 45, is the bevel gear 47; the said bevel gear 55 by means of the bevel pinion and shaft 48, drives the sprocket 49. The sprocket 49, in turn becomes the means of operating the endless carrier chain 50; the said chain passes under the idler sprocket 51, and over 60 the idler sprocket 52, thus making it possible to use the same chain to discharge the cans that load the machine. At the outer ends of table are installed other idler sprockets over which the endless carrier chain 65 passes that it may return under the table;

the said sprockets are not shown in the drawings.

Mounted on the base and rigidly secured thereto are the pockets for the adjustable pillars 53, 54, 55, 56. The said pillars are 70 arranged on either side of the revolving head of the machine in a suitable position for the purpose required. At the top of said pillars and at right angles to the same, the slotted bearings 57, and 58, are mounted; 75 the same being a suitable distance apart to provide for the operation of the rocker arm. Slidably mounted in the bearing 57, is the spring plunger 58', having in the side thereof the pin 59, operating in the slot 60. Movably mounted in the bearing 58, is the sliding member 61, having on its inner end the arcuated head 62, and in the side thereof the pin 63, operating in the slot 64.

By means of the rocker arm 65, oscillating on the central bearing 66, with its elongated holes 67, 67, engaging the pins 59, and 63, an alternating movement is imparted to the spring plunger 58, and the sliding member 61, that is utilized in the following manner: As the can D, (carried by means of the depression 11, in the flange of the carrier head 9,) passes the arcuated head 62, of the sliding member 61, it forces the said member with the rocker arm connected thereto, into 95 the position indicated by the slotted line X. This movement causes the spring plunger 58', to move forward until the point thereof, indicated by the numeral 68, assumes the position shown by the dotted line Y. In this position the said point engages one arm of the star head controlling the valve 7, moving the same one quarter turn. This movement taking place at the first pillar 53, opens the two-way valve to the vacuum pipe line. 100 The same operation is repeated at the second pillar 54, at which point the valve closes the vacuum pipe line and opens the syruping pipe line, the same remaining open until the carrier head has made approximately one half 105 turn. At the pillar 55, the movement of the parts described is repeated, the valve now closing the syruping pipe line. At the pillar 56, the repeated movement of the mechanism places the valve in position to be opened for the vacuum at the pillar 53. Should one or 110 more of the spaces in the carrier head be empty, the said space passes the arcuated head of the sliding member 61, at all the stations thereof without operating the valve. 115 As the cans are passed into the carrier head by the loading gear 45, the plunger 12, raises them into air-tight contact with the elastic cap 14, by means of the incline 69, on the differential rail 17. The rail maintains them 120 in this position until they have passed the closing mechanism at the pillar 55.

The power to operate the machine as well as the suction required to produce the vacuum may be supplied in the ordinary manner. 130

The advantages of the device are apparent. The can to be syrped requires but a small opening to be operated on by my machine, this insures quick and easy sealing 5 while the extraction of the air from the can leaves it in a condition to receive the liquid. As to the rapidity of operation it can be readily seen that the ceaseless moving of the cans through the machine and their dis- 10 charge therefrom can only be productive of the highest efficiency.

I do not wish to be understood as confining myself to the precise construction shown herein, but wish to avail myself of any modifications that may fall properly within the 15 scope of my invention.

Having thus described my invention, what I claim as new and desire to secure by Letters Patent, is,

20 In combination, a rotating syrping head with a double reservoir, comprising an upper syrup chamber and a lower vacuum chamber, a syrup supply source, a vacuum creating source, a filling head provided with 25 a two-way valve, pipe connections leading from said syrup chamber to said syrup sup-

ply source, a hollow shaft communicating with said vacuum chamber of the reservoir at its upper end and at its lower end communicating with said vacuum creating 30 source, separate pipe connections between the syrup and vacuum reservoir chambers and said two way valve of the filling head, and means automatically operated by the rotation of the syrping head for controlling 35 said two way valve comprising a star head carried by the valve, an arm for actuating said head held normally pressed outward, a second arm positively operated by the can, a lever between the arms to communicate 40 the movement of the lower arm to the upper and force the upper inward, the said lower arm having means projecting into the path of the cans, to be actuated thereby when a can is in position on its supporting head, substantially as described.

In testimony whereof, I affix my signature in presence of two witnesses.

WILLIS GRANT MURRAY.
